FLAT KNITTING FRAME

Arthur Richter, Berbisdorf Post Einsiedel, near
Chemnitz, GermanyApplication March 17, 1934, Serial No. 716,188
In Germany February 8, 1934

4 Claims. (Cl. 66—89)

This invention relates to a flat knitting frame, especially to a full-fashioned hosiery machine.

The narrowing machine, carrying also the lock-stitch attachment, the lace-clock attachment etc., is disposed above the spring beard needles, when in inoperative position. In this inoperative position the narrowing machine is held by round cams arranged beside the cams for raising and lowering the narrowing machine. The motions of the covering needles from the inoperative position to the lowest position and back again are necessarily greater than the rising and lowering motions of the spring needles, and to avoid having to reduce the working speed of the machine during narrowing, it has been proposed to cause the covering needles to carry out vertical movements also while the camshaft is not racked. According to the present invention the cams on the cam shaft are arranged to cause the covering needles, which stand before fashioning in inoperative positions above the spring needles, to commence their downward transfer movements before the cam shaft is racked. The covering needles thus are relatively independent as to these motions from the racking of the camshaft, and it becomes possible to have the covering needles carry out during racking only the actual working motions while the motions required for rendering the covering needles operative and inoperative are effected before or after the rocking of the main shaft. There will thus be sufficient time before and after racking slowly to bring the covering needles into initial working position and back again, and the covering needles motions during racking may be slowed down also, since in this machine position the covering needles move only from initial working to low position and back to a position corresponding to the initial position.

One form of the invention is illustrated in the accompanying drawing, in which Figure 1 is a diagrammatic oblique view of the parts serving to actuate the narrowing machine and Figs. 2, 3 and 4 are detail views of various positions of the knitting tools.

In order to make it possible to carry out the motions of the covering needles more slowly than can be done at present when the camshaft 2 is racked, the needles 1 are vertically adjusted, according to the invention, also when the camshaft is not racked. In the example shown, the covering needles 1, when the camshaft 2 is racked, are brought only from their initial working position to their low position and back again to a position corresponding to the initial working position, whereas the motions from the latter to

inoperative position and thence to initial working position are carried out when the camshaft 2 is not racked. The distance covered by the needles 1 from inoperative to initial working position amounts to approximately 50% of the total distance, and as the respective motion is carried out already before racking of the camshaft 2, it is evident that during the subsequent racking approximately 50% more time is available for the motion of the covering needles 1 from initial working to low position than was possible hitherto.

To carry out this subdivision of the motions of the covering needles 1 two cams 4, 5 in addition to the usual rotary disc 3 are provided on the camshaft 2 for imparting vertical motions to the narrowing machine 6. The rotary disc 3 cooperates with a roller lever 8 disposed on the narrowing shaft 7 and the cams 4, 5 control the roller lever 9 oscillatorily arranged in the front portion of the machine and acting on the narrowing machine 6 by means of the vertical bar 10, the arrangement being such that the roll 11 of the lever 8, when the camshaft 2 is not racked, is carried by the disc 3 so as to hold the narrowing machine 6 and the needles 1 thereof in inoperative position, as indicated in Fig. 2. During racking of the camshaft 2 in the direction of the arrow the roll 11 would be released by the rotary disc 3; but it is axially displaceable to the left and thus capable of becoming disengaged from the disc 3 before the main shaft 2 begins to rack. When the main shaft is not racked the roll 12 of the lever 9 is carried by the cam 4 and, during racking, passes to the cam 5. The cam 4 makes possible the rising and lowering motions of the narrowing machine 6 or the covering needles 1 thereof from inoperative (Figs. 1 and 2) to initial working position and back again (Fig. 4), and the cam 5 causes the motions of the narrowing machine 6 and the covering needles 1 from initial working (Fig. 4) to the normal low position and back again.

Referring to Fig. 1, the narrowing shaft 7 is connected with the narrowing machine 6 by means of the arms 18 at 19. These arms 18 seat by means of one end securely on the narrowing shaft 7 and the narrowing machine 6 is suspended on the other end of the arms. The shaft 7 takes part in the up-and-down movements of the narrowing machine 6 insofar as the shaft 7 turns. If the lever 8 with its roll 11 is influenced by the rotary disc 3, then the narrowing shaft 7 will be held secure in such turned position so that the arms 18 will maintain the narrowing machine 55

6 in its upper position. If, however, the influence of the rotary disc 3 is removed from the lever 8 then this lever and its roll 11 will remain freely suspended as the roll 11 is axially shiftable on the lever 8 and therefore the lever 8 with its roll 12 will be influenced by its cams 4 and 5 and lifts and lowers the narrowing machine 6 by means of the vertical bar 10 which is connected with the narrowing machine 6 at 20. The lever 8 with its roll 11 will remain freely suspended during this time.

The device functions as follows:

Assumed plain courses are being worked requiring no racking of the camshaft 2, so that the 15 rotary disc 3 holds the narrowing machine 6 and the covering needles 1 in inoperative position. In the next course narrowing is to be effected, and the roll 11 is therefore drawn to the left from the rotary disc 3. The position of the camshaft 20 2 is now such that the roll 12 of the lever 8 rests on the arc portion 13 of the cam 4, the radius of the arc 13 coinciding with the radius of the rotary disc 3. The withdrawal of the roll 11 from the disc 3 is thus accompanied by transfer of the 25 actuation of the covered needles to the cam 4 without causing racking of the camshaft 2 and the cam 4 lowers the narrowing machine 6 or needles 1 into initial working position (Fig. 4), which might take place when the spring needles 30 14 go down for pressing (Fig. 3). When the spring needles 14 are in knocking over position, the covering needles 1 will move already into initial working position, as indicated in Fig. 4, where the camshaft 2 will be racked whereby the spring needles 14 will receive the known necessary motions and the roller lever 9 pass under the control of the cam 5 which will lower the covering needles 1 and then raise them again to a position corresponding to initial position. When the 35 40 covering needles have reached this latter position, return racking of the camshaft 2 takes place whereby the cam 4 is actuated again. By returning the roll 11 the cam 4 is then replaced again by the disc 3.

If covering is carried out uninterruptedly, the disc 3 is not actuated again during the production of the goods, and the roll 11 remains constantly near the disc 3 to the left thereof.

I claim:—

50 1. A flat knitting frame comprising fashioning mechanism with vertically reciprocating covering needles, spring needles cooperating with the covering needles, a cam shaft capable of being

racked during fashioning, and a cam on said shaft for causing covering needles standing before fashioning in their inoperative positions above the spring needles to commence their downward transfer movements before the cam shaft is 5 racked.

2. A flat knitting frame comprising fashioning mechanism with vertically reciprocating covering needles, spring needles cooperating with the covering needles, a cam shaft capable of being 10 racked during fashioning, and cams on said shaft, one of said cams causing covering needles standing before fashioning in their inoperative positions above the spring needles to commence their downward transfer movements before the cam 15 shaft is racked and the cams being so shaped and arranged that during the racking of the cam shaft the covering needles are brought only from an initial working position to a low position and back to a position corresponding to the initial 20 working position and the motions of the covering needles from inoperative to initial working position and back again taking place before the racking and after the return of the cam shaft respectively.

3. A flat knitting frame comprising fashioning mechanism with vertically reciprocating covering needles, spring needles cooperating with the covering needles, a cam shaft capable of being 30 racked during fashioning, a rotary disc on the cam shaft for holding the covering needles in inoperative position, and two cams disposed on said shaft, one of said cams controlling the raising and lowering motions of the covering needles from inoperative to initial working positions and back again and the other cam controlling the motions of the covering points from initial working 35 to low positions.

4. A flat knitting frame comprising fashioning mechanism with vertically reciprocating covering 40 needles, spring needles cooperating with the covering needles, a cam shaft capable of being racked during fashioning, a rotary disc on the cam shaft for holding the covering needles in inoperative positions, two cams disposed on said shaft, one 45 of said cams controlling the rising and lowering motions of the covering needles from inoperative to initial working positions and back again and the other cam controlling the motions of the covering needles from initial working to low positions, and means for rendering said rotary disc ineffective during continued fashioning.

ARTHUR RICHTER.
